BEVERAGE DISPENSING MACHINE

José Arturo Conde, Independence, Mo., assignor to The Vendo Company, Kansas City, Mo., a corporation of Missouri

Filed June 10, 1965, Ser. No. 85,656

Term of patent 7 years

(Cl. D52—3)

Fig.2.

Fig.4.

FIG. 1 is a perspective view of the front and one side of a beverage dispensing machine, showing my new design;

FIG. 2 is a front elevational view thereof;

FIG. 3 is a side elevational view showing the side opposite to that shown in FIG. 1; and

FIG. 4 is a front perspective view showing the front and one side of a modified form of the beverage dispensing machine.

The undisclosed side of FIG. 4 is the same in appearance as the side shown in FIG. 3, except for the omission of the rack portion.

The horizontal dash lines on the grill panel in FIGS. 1, 2 and 4 are intended to represent a continuation of the spaced rows of short vertical lines.

The rear of the beverage dispensing machine of both embodiments is substantially plain in appearance, except for the presence of conventional access doors.

I claim:

The ornamental design for a beverage dispensing machine, substantially as shown and described.
